UNITED STATES PATENT OFFICE

CHARLES C. ARMSTRONG, OF HUNTINGTON, WEST VIRGINIA, ASSIGNOR TO THE ARMSTRONG ELECTRIC AND MANUFACTURING CORPORATION, OF HUNTINGTON, WEST VIRGINIA, A CORPORATION OF WEST VIRGINIA

DESIGN FOR A COFFEE PERCOLATOR

Application filed December 26, 1929. Serial No. 33,919. Term of patent 14 years.

To all whom it may concern:

Be it known that I, CHARLES C. ARMSTRONG, a citizen of the United States, residing at Huntington, in the county of Cabell and State of West Virginia, have invented a new, original, and ornamental Design for Coffee Percolator, of which the following is a specification, reference being had to the accompanying drawing, forming part thereof.

Figure 1 is a side elevation of a coffee percolator showing my new design;

Figure 2 is a plan view; and

Figure 3 an end elevation thereof.

I claim:

The ornamental design for a coffee percolator, as shown.

CHARLES C. ARMSTRONG.
